UNITED STATES PATENT OFFICE.

CLIFTON F. LEATHERBEE, OF NEWTON, MASSACHUSETTS, ASSIGNOR TO PAINTING MACHINE COMPANY, OF KITTERY, MAINE, A CORPORATION OF MAINE.

WOOD-TREATING MACHINE.

1,167,417.

Specification of Letters Patent. Patented Jan. 11, 1916.

Application filed February 10, 1909. Serial No. 477,051.

To all whom it may concern:

Be it known that I, CLIFTON F. LEATHERBEE, a citizen of the United States, residing at Newton, in the county of Suffolk and 5 State of Massachusetts, have invented certain new and useful Improvements in Wood-Treating Machines, of which the following is a specification.

My invention relates to machines for applying liquids or fluids to the surfaces of 10 materials, and particularly to the provision of an improved type of apparatus which is adapted to paint, stain, varnish, fireproof, creosote, weatherproof and otherwise treat 15 materials or generally subject to the action of liquids, flooring, molding, cross arms and other lengths of wood or strips of moving material and for polishing and finishing the same, coating them with insulation, etc.

20 The principal objects of my invention are the provision of a machine of the class described which is adapted to apply the liquid rapidly, easily and economically, and to apply it with facility and thoroughly to all the 25 surfaces of material of irregular contour, especially such strips as picture molding, wainscoting wall rails, conduit molding adapted to carry electrical wires, and the like; to provide a machine which is adapted 30 for applying a liquid to the edges of boards, and for thoroughly cleaning the material before it is treated and for rubbing the liquid in and removing the excess, after it is treated; to provide means whereby the excess material 35 may be removed from the machine to the supply tank and reused in order to avoid wastage, together with such other objects as will hereinafter more fully appear.

For the accomplishment of the objects 40 above referred to, together with such other objects as will readily occur to those who are skilled in the art to which my invention pertains, I have provided the construction illustrated in the accompanying drawings, 45 wherein—

Figure 1 is a sectional elevation of a preferred form of my invention, taken on the line I—I of Figure 2.

Figure 2 is a plan view of the machine of 50 Figure 1 taken on the line II—II thereof.

Figure 3 is a sectional elevation taken on the line III—III of Figure 2 to illustrate the means for supplying the liquid to the machine.

Figure 4 is a sectional view taken on the 55 line IV—IV of Figure 2, to illustrate the contact of one of the finishing brushes when the liquid is to be applied to but a single surface of the moving material, certain of the parts appearing in Figures 1 and 2 having 60 been removed.

Figures 5 and 6 are respectively sections taken on the lines V—V and lines VI—VI of Figure 2 to illustrate the adjustable mounting of the upper brushes and rolls. 65

Figures 7 and 8 are respectively a longitudinal sectional elevation taken on the line VII of Figure 8, and a plan sectional elevation taken on the line VIII of Figure 7, to illustrate my preferred form of construction simplified for the purpose of treating 70 the moving material on but a single plane or surface.

Referring to Figures 1 and 2 it will be seen that in carrying out my invention, I 75 provide a box like structure or casing 10 which I preferably locate adjacent the end of a planer or other machine for forming molding, flooring and the like. In order to save the expense and delay incident to a 80 rehandling of the material and to insure a straight feed of the material to be treated through the machine, it should be fed by the live rolls of the forming machine, though it will be apparent that if it is desired to use 85 my machine separately from the forming machine, the material to be treated may be readily fed through a machine of my construction by the live rolls 11 and 12 located adjacent thereto or other convenient means. 90

For the purpose of cleaning the moving material in order that it may be properly prepared for the reception of the liquid, and that the effective application thereof may not be interfered with by the presence of 95 dust, chips, shavings or other detritus, I provide the oppositely disposed pair of brushes 19 and 20, and in order that the waste removed from the moving material thereby may not clog the machine, the casing 10 is left open at the bottom beneath such brushes as indicated at 21.

For the further polishing of the material preliminarily to the application of the liquid a second set of brushes is provided as indicated at 23, 24, and to thoroughly rub in 105 and incorporate the liquid with the surface of the moving material after removing any

excess thereof, another oppositely disposed set of brushes 25 and 26 is arranged at the tail end of my machine.

To assure the application of the treating liquid to the sides and edges of the moving material as well as to the broad or plane surfaces thereof, I provide preferably at right angles to the brushes heretofore described a pair of oppositely disposed brushes 27 and 28.

Referring particularly to Figures 1 and 3 it will be noted that to facilitate the application of the treating liquid, I have provided the tank 30 from which the liquid may be fed by the piping 31, 32 and 33 to the oppositely disposed spraying nozzles 35 and 36. The orifices of such nozzles being regulable by the valve devices indicated at 37 and 38 respectively and the volume of the liquid supplied thereto being further controllable by the globe valves indicated at 39 and 40.

When the nature or purpose of the moving material to be treated is such that it is desirable to apply the liquid to but a single surface thereof, the valves 39 and 40 may be closed and the liquid fed to the brush 22 from the pipe 34 connected to the pipe 31 and controlled by the valve 42. From an inspection of Figure 1 it will be seen that the nozzle or end of the pipe 34, is so embedded in the brush 22 as to allow the liquid to feed the bristles of the brushes and thence, to be supplied to the surface of the moving material, in such a manner as to prevent it from spattering and to confine it immediately to the surface which is in contact with such bristles.

To facilitate the removal of any excess of liquid given forth from the nozzles 35 and 36, or that may be removed from the moving material by the brushes 25 and 26, I provide the casing 10 with a sloping bottom which drains into the trap 43 connected by the pipe 44 to a pump 45 which may be of any convenient type adaptable for the purposes of my invention. The pump 45 is connected by the pipe 46 to the tank 30 for a two fold purpose; in the first place to return thereto the excess liquid from the trap 43 in order that it may not be wasted, and, second, to supply pressure to the tank 30 in order to force the liquid therefrom into the pipe 31, and thence to the nozzles 35 and 36. It will, however, be apparent that various other feed arrangements might be used, depending upon the character of the paint or stain used and of the material treated.

By reference to Figures 1, 5 and 6 it will be noted that the rolls 14, 16 and 18 which serve to support the moving material, or both to support and feed it, as well as the brushes 20, 24 and 26 which act upon the lower side of such material are removably fixed in position but are not necessarily ad-

justable, whereas the corresponding rolls 13, 15 and 17 are vertically adjustable in order that materials of different sizes and diameters may be fed through the machine and maintained in desired position, such adjustability being obtained by the respective engagement of the bolts 47—47' with the slots 48—48' in the yoke 49, in which the ends of the shaft 50 carrying the roll are mounted, (see Figure 6), and the brushes 19, 23 and 25 are likewise capable of vertical adjustment to facilitate the passage of the moving material, such adjustment being obtained by the respective engagement of the bolts 57—57' with the slots 58—58' in the yoke 59 in which the back 60 of the brush 19 is carried. When the rolls and brushes have been adjusted to the desired positions they may be fixed therein by tightening up the nuts 51—51' and 61—61' respectively.

From an inspection of Figures 1 and 3 it will be further apparent that the brushes 27 and 28 are adjustable laterally by the screws 67 and 68 which have threaded engagement with the sleeves 69 and 70 in the sides of the casing 10 and through the slots 71 and 72 with the blocks 73 and 74 in the brushes 27 and 28 respectively. These brushes may also be lifted and lowered vertically, for a purpose which will herein-after appear, by means respectively of the screws 75 and 76 having threaded engagement with the sliding sleeves 77 and 78 carried in the slots 79 and 80 in the top of the casing 10.

It will be observed from Figures 3 and 5, as well as from Figures 1 and 2, that the pairs of brushes, 19—20, 23—24, 27—28 and 25—26 are made of irregular contour by the provision therein of series of tufts of bristles of materially different lengths, (81—82), which I have found it desirable to provide for a number of reasons, among others that by this serrated form of brush the liquid may be applied to moving materials of all contours however irregular, and through the interlocking of the serrations in the edges of the oppositely disposed brushes the moving material is fully encompassed and no part thereof can escape the application of the liquid.

It will be further seen that a vertical adjustment of the brush 22 may be had, where expedient, on account of the contour of the material to be treated, by loosening the ring 83 and moving the split friction sleeve 84, (see Figures 1 and 7), and that the nozzles 35 and 36 may likewise be adjusted vertically where the contour of the moving material or the gravity or viscosity of the liquid renders it desirable.

From an inspection of Figures 1, 2 and 4 it will be noted that when it is desired to apply liquid to but a single surface of a piece of moving material, as for example

the underside of a piece of flooring 87, (which is run upside down, as will appear from Figure 4, since the finishing head of the flooring machine is on the under side 5 thereof, resting directly on the body of the machine in order to obtain the minimum vibration), that is to say the upper side of the flooring as it comes from the machine, I have provided the longitudinal tongued 10 and grooved members 88 and 89 adapted respectively to engage with a corresponding groove and tongue on the moving material 87, the said members 88 and 89 being provided with felt strips 90—91 in order to 15 prevent any excess liquid which may be applied to the flooring 87 by the brush 22 from passing beyond the said tongues and grooves and thereby staining or discoloring the opposite surface of the flooring 87. As 20 may be seen most clearly in Figure 4, the members 88 and 89 are adjustable laterally by the screws 92 and 93 which have threaded engagement with the sleeves 94 and 95 in the sides of the casing 10, the said screws 25 92 and 93 being respectively provided with lock nuts 96 and 97 in order to hold the members 88 and 89 firmly in place when they have been properly adjusted to receive flooring of the dimension then to be treated. 30 It will be, further observed from Figure 6 that the various series of rolls such as 15 and 16 are preferably made in three sections 98, 99 and 100 in order that when the supporting members 88 and 89 are used they 35 may respectively rest upon the at that time dead outer portions 98 and 99 while the flooring 87 rides upon the live portion 100, though I have found that equally satisfactory results may be attained in the case of 40 flooring by the use of the simplified form of construction illustrated in Figures 7 and 8 wherein the members 88 and 89 are supported at the opposite ends on the casing 10 and upon the inner partition wall thereof 45 10^a.

It is to be understood that while I have illustrated the members 88 and 89 as adapted to receive tongued and grooved flooring they may be readily adapted to receive material of other cross section which requires treatment on only part of its superficial area. The arrangement of tongue and groove members provided with absorbent or damming strips will be found particularly 50 useful in connection with machines which supply to the treating machine material of 55

extraordinary lengths, as for example veneering machines, and especially on such occasions as it may be found desirable to stop the machines while they contain material in the process of formation and treatment. 60

The mode of operation of the machine embodying my inventions and the benefits and advantages thereof will be apparent from 65 the foregoing description of its purposes and construction, to those who are skilled in the art.

Having thus described my invention and illustrated its uses what I claim as new and 70 desire to secure by Letters Patent is the following:—

1. In a machine for treating moving material, in combination, a casing adapted to receive moving material, means for guiding the edge of the material, means for applying liquid to part of the material and means coöperating with the said guiding means preventing the application of the liquid to other parts of the moving material. 75 80

2. In a machine for treating moving material, in combination, a casing adapted to receive moving material, means for applying liquid to part of the moving material, a pair of strips for guiding the moving material, and felt strips on the said guides. 85

3. In a machine for applying a liquid to one face of tongue-and-groove boards, guide means fitting the edges of the boards and protecting them, and a brush adjacent 90 the face of the board.

4. In a machine for treating material, the combination with means for supplying liquid to the material, of a brush having an irregularly serrated contour whereby the 95 end portions of the longest bristles can flex independently of the shorter.

5. In a machine for treating material, the combination with means for supplying liquid to the material, of a brush having 100 tufts of bristles of pointed or jagged contour whereby the bristles forming the end portions of said tufts can flex independently of the shorter bristles.

In testimony whereof I have hereunto 105 signed my name in the presence of the two subscribed witnesses.

CLIFTON F. LEATHERBEE.
